UNITED STATES PATENT OFFICE.

JULIAN F. DRAKE, OF TRACY, MINNESOTA.

DETACHABLE BOILER-FLUE.

SPECIFICATION forming part of Letters Patent No. 718,609, dated January 20, 1903.

Application filed May 27, 1902. Serial No. 109,132. (No model.)

To all whom it may concern:

Be it known that I, JULIAN F. DRAKE, a citizen of the United States, residing at Tracy, in the county of Lyon and State of Minnesota, have invented certain new and useful Improvements in Detachable Boiler-Flues; and I do hereby declare the following to be a full, clear, and exact description of the invention, such as will enable others skilled in the art to which it appertains to make and use the same.

My present invention relates to detachable boiler-flues, and is in the nature of an improvement on the device set forth and claimed in my prior patent, No. 696,421, of April 1, 1902.

The invention consists of the novel devices and combinations of devices hereinafter described, and defined in the claim.

The invention is illustrated in the accompanying drawings, wherein like characters indicate like parts throughout both views.

Figure 1 is a view, principally in vertical section, with some parts left in full and others broken away, showing a flue and novel means for securing the same to the flue-sheets; and Fig. 2 is a face view of the annular clamping-nut removed from working position.

The numeral 1 indicates the flue-sheets of a boiler and the numeral 2 one of the flues. At one end the flue is secured to the flue-sheet by a novel device, which is the subject of my present invention. As shown in the drawings, this novel device is applied to the left-hand end of the flue, while at its right-hand end the flue is shown as connected to the flue-sheet by means of a device which was disclosed and claimed in my prior patent, No. 698,471, dated April 29, 1902. This latter device comprises an inwardly-tapering or slightly-conical sleeve 3, which is preferably brazed to the end of the flue, and a thin packing ring or collar 4, preferably of copper. The said packing-ring 4 is adapted to be tightly pressed between the tapered sleeve 3 and the seat 1^a, formed therefor in the right-hand flue-sheet. Since this device forms no part of my present invention, the foregoing brief description thereof is deemed sufficient.

The novel device shown at the left-hand end of the flue comprises the collar 5, a loose clamping-ring 6, and clamping-nut 7. The

collar 5 is brazed to the end of the flue 2 and passes through a quite closely-fitting seat 1^b in the left-hand flue-sheet 1. At its outer end the collar 5 is provided with screw-threads, on which the nut 7 works. The clamping-ring 6 loosely surrounds the collar 5, between the clamping-nut 7 and the adjacent flue-sheet, and on its inner edge it is provided with an annular groove, in which is placed a packing of asbestos or similar pliable and non-fusible material, (indicated at 8.)

As is evident, when the parts are applied as shown in Fig. 1 and the clamping-nut 7 is tightened against the clamping-ring 6 the packing 8 will be tightly compressed both against the flue-sheet and the collar 5 and will form steam-tight joints therewith.

When a number of adjacent flues of a boiler are applied as above described, the clamping-nuts 7 will come very close together, and hence the said nuts should be made round or of annular form and should be provided with notches or seats 7^a, to which the pins or lugs of a suitable wrench may be applied to turn the nuts.

In my prior patent, No. 696,421, threads were cut directly on the ends of the flue. These threads of course weakened the flue more or less. In my present device the threads are cut on the collar 5, and the said collar reinforces and strengthens the end of the flue and enables the same to withstand pounding, such as may be necessary to drive the same out of its seats in the flue-sheets after it has stood for a long time and become corroded and covered with scale.

The seat 1^a in the right-hand flue-sheet should be large enough to permit the flue to be withdrawn therethrough when covered with about an eighth of an inch of scale, and it must also, of course, be of such size as to pass the collar 5 when the clamping nut and ring are removed therefrom.

The necessity for frequently removing flues of boilers, and especially of boilers used in alkali districts, is, as is well known, occasioned by the rapid collection thereon of scale, which greatly reduces the heating efficiency of the boiler.

What I claim, and desire to secure by Letters Patent of the United States, is as follows:

In a boiler, the combination with a flue-

sheet 1 having a flue-seat 1^b, of the detachable flue 2, having the permanently and rigidly secured collar 5 affording an enlargement thereof and telescoping through said seat 1^b, the clamping-nut 7 screw-threaded on the outer end of said collar 5, and the clamping-ring 6 loosely fitting said collar 5 between said clamping-nut and said flue-sheet and provided with the annular packing 8 of non-

fusible material, tightly pressed against the 10 flue-sheet and said collar and forming steam-tight joints therewith.

In testimony whereof I affix my signature in presence of two witnesses.

JULIAN F. DRAKE.
